ABSTRACT OF THE DISCLOSURE

An electric generator of the type having a movable armature actuated by an internal combustion engine. The armature surrounds and is coaxial with a rod connected to the piston of the internal combustion engine. Gears support and drivingly engage the armature and the rod such that they reciprocate in opposite directions. The mass of the armature, the piston and the piston rod are selected such that forces created by movement of the piston and piston rod in one direction are balanced by forces created by the movement of the armature in the opposite direction.

BACKGROUND—FIELD OF THE INVENTION

This invention relates to electric generators, and in particular, it relates to electric generators of the type actuated by an internal combustion engine.

BACKGROUND—DESCRIPTION OF THE PRIOR ART

Electric generators are known wherein the moving parts of the generator are actuated by an internal combustion engine, and particularly by engagement between the moving parts of the generator and the piston of the internal combustion engine. Moreover, these previously known devices include attempts to balance the forces created by the movement of the moving parts of the engine and the generator. However, complete balancing of these forces has not been possible. Consequently, with existing generators of this type it has been necessary to employ relatively strong mountings for supporting not only the weight of the generator and the engine, but also the residual forces resulting from the imperfect balancing out of the forces.

Thus, there exists a continuing need to provide an electric generator of the type actuated by an internal combustion engine but characterized by a more perfect balance between forces derived from the moving parts of the generator and forces derived from moving parts of the internal combustion engine.

SUMMARY OF THE INVENTION

Thus, it is a purpose of the present invention to provide an electric generator actuated by an internal combustion engine wherein the disadvantages associated with imperfect balancing of forces have been substantially eliminated, whereby the overall size of the electric generator and its mounting means may be substantially reduced. Further, in view of the more perfect balance of the forces created by the moving masses, any frequency of operation can be employed and the apparatus can be mounted at any location on either a surface vehicle or an airplane since the means for mounting the generator on the vehicle is essentially strained only by its own weight.

According to the present invention the center-line, or axis of a longitudinally extending, free floating piston (or pistons) of the internal combustion engine is arranged to be coincident with the center-line or axis of the free floating moving parts of the electric generator, (which also move in the longitudinal direction). The mass of the piston and the piston rod are substantially equal to the mass of the moving parts of the generator and the said

2

rod is drivingly engaged with the moving parts of the generator through gear means such that movement of the piston rod in one direction causes the moving parts of the generator to move in the opposite direction.

For providing this movement the piston rod connected to the piston includes on its outer surface at least one toothed rack and preferably a plurality of toothed racks. Corresponding toothed racks are formed on the moving parts of the generator. Gear means mounted in a fixed casing between the rod and the movable parts of the generator provide the said driving engagement between the rod and the moving parts of the generator.

A further feature of the invention includes the arrangement whereby the movable parts of the generator, and specifically the armature of the generator, surrounds the casing and is supported only by the said gear means which drivingly engages the armature with the said rod. To prevent play in the gear means, the gears may be connected to other parts of the vehicle in which the generators is mounted, such as the steering wheel or the like.

The internal combustion engine employed with the electric generator of the present type may be of any known design. For example, it may be a double-acting two stroke piston engine or it may include a pair of double-acting pistons working in opposite directions. The bottom of each piston can also be used for scavenging the upper half of the cylinder. A four-stroke operation is also possible.

Since the armature of the generator is mounted concentrically about the axis of the piston rod, and since the armature is supported solely by the said gears, then it is possible to permit the pistons to operate with a slight amount of play in the cylinders. Normally the same frequency of operation is maintained independent of the strain to which the device is placed. The internal combustion engine may also include a flow packing arrangement whereby lubrication of the internal combustion engine pistons becomes unnecessary.

Thus, it is an object of this invention to provide a new and improved electric generator of the type actuated by an internal combustion engine wherein the forces created by the moving parts are substantially balanced out such that the sole force exerted on the mounting elements is the weight of the apparatus itself.

It is another object of the invention to provide an electric generator of the type operated by an internal combustion engine wherein the armature of the generator is coaxial with the piston rod of the internal combustion engine.

It is still another object of this invention to provide an electric generator of the type actuated by an internal combustion engine wherein the armature of the electric generator is supported and centered solely by the means connecting it to the piston rod with which it is co-axial.

Other objects and the attendant advantages of the present invention will become apparent in the detailed description to follow, together with the accompanying drawings.

BRIEF DESCRIPTION OF THE DRAWINGS

There follows a detailed description of a preferred embodiment of the present invention to be read together with the accompanying drawings. However, it is to be understood that this detailed description and the accompanying drawings are provided solely for purposes of illustrating a preferred embodiment of the invention and that variations and modifications are capable within the spirit and scope of the invention.

IN THE DRAWINGS

FIG. 1 is a longitudinal sectional view of an electric generator constructed in accordance with the present invention and taken along lines C-D of FIG. 2.

FIG. 2 is a cross-sectional view of an electric generator constructed in accordance with the present invention and taken along lines A-B of FIG. 1.

DETAILED DESCRIPTION OF THE PREFERRED EMBODIMENT

Referring now to the drawings, there is shown an electric generator constructed in accordance with the present invention. A pair of pistons 1 and 2 are connected together through piston rod 5 and are operable within internal combustion chambers 7 and 8. Each piston includes a pair of annular grooves 3 and 4, one on each side thereof, for producing the whirls of gas necessary for providing flow packing within the chambers. Each of the internal combustion chambers 7 and 8 include inlet passages 10 selectively opened by valve members 9 opening into an enlarged overflow portion 11 of the chambers 7 and 8. At the opposite end of each chamber there is provided a fuel injection nozzle 13 and an outlet passage 12 controlled by an electrically operated valve member 12.

FIG. 1 shows the internal combustion engine immediately prior to combustion beneath the lower piston 2. This combustion will move the pistons 1 and 2 and the piston rod 5 upwardly. As the pistons and the piston rod move upwardly, the spent gases in chamber 8 are cleared through an outlet opening by the scavenging action of piston 1. When the scavenging action has been completed valve 12 is closed and the gases present at the upper end of the chamber 8 are compressed for subsequent combustion above the piston 1 thereby causing downward movement of the pistons 1 and 2 and the piston rod 5. The same scavenging action then takes place below the lower piston 2 and the cycle is repeated. In practice, however, many other types of internal combustion engines may be employed instead of the two-piston two-stroke engine shown herein.

The piston rod 5 includes a rack portion 6 having four rack surfaces formed about its periphery. A fixed casing member 14 surround the rod and has formed therein gears 15, 16, 17 and 18, each mounted in casing 14 for rotational movement about a fixed axis and each associated with one of the four racks formed on the surface of the portion 6.

Surrounding the casing member 14 are the generator parts including a fixed stator 26 having fixed stator windings 24 and 25, and an annular armature member 23 surrounds the casing 14 within the stator 26.

Longitudinal movement of this armature (upwardly and downwardly as viewed in FIG. 1) relative to the stationary stator windings 24 and 25 induces a current in the windings and thereby generates electricity in accordance with the main purpose of the generator. The armature 23 has affixed thereto a plurality of toothed racks 19, 20, 21 and 22 which engage gears 15, 16, 17 and 18, respectively.

For simplicity, the teeth on the various racks have been shown symbolically in FIG. 1. However, were these shown in detail, then the crests and grooves of the teeth of the two racks of portion 6, as well as the teeth on gears 16 and 17 and on racks 18 and 21 would be visible in FIG. 1.

It can be seen from the drawings that the armature 23 is mounted to be actuated by movement of the rod 5 in a direction opposite to movement of the rod 5. It can also be seen that armature 23 is "floating" in that it is supported and centered about the same axis as that of rod 5 solely by its engagement with gears 15, 16, 17 and 18. The member consisting of pistons 1 and 2 and rod 5 is also "floating" in that it is supported only by its engagement with gears 15, 16, 17 and 18 (except, of course, for the stabilizing effect brought about by the confinement of the pistons 1 and 2 within the chambers 7 and 8).

The operation of the invention is as follows. The internal combustion engine is operated to reciprocate the piston rod 5 and thus the rack portion 6 longitudinally, this movement causing equal and opposite longitudinal movement of the armature 23. Since the mass of armature 23 and the mass of the member consisting of elements 1, 2 and 5 are located on a common centerline, the forces created in the longitudinal direction by movement of the pistons and piston rod will be cancelled out by the forces created in the longitudinal direction by the equal and opposite movement of the armature 23. This balancing out is further enhanced by the fact that the armature and the piston rod are "floating." This floating connection keeps the armature and the rod parallel with each other even though these elements may move angularly a slight amount relative to the original axis when the elements are at rest.

Although a preferred embodiment of the invention has been illustrated and described in considerable detail, it should be apparent that the present invention is capable of numerous modifications and variations apparent to those skilled in the art without departing from the spirit and scope of the invention as defined in the claims.

I claim:

1. In an electric generator of the type wherein the movable part of the generator is driven by an internal combustion engine having a piston means mounted to be reciprocated along its axis in a longitudinal direction, the improvement wherein, the movable part of the generator is also mounted for reciprocating movement in said longitudinal direction, and wherein the center of mass of both the piston means and the movable part are located on and are movable along the same said axis, connecting means for positively connecting together said piston means and said movable part of the generator such that movement of the piston means causes movement of said movable part of the generator in the opposite direction, wherein the force of said piston means moving in said longitudinal direction is balanced by the force of the movable part moving in the opposite direction.

2. The invention of claim 1 wherein said piston means includes at least one piston operable in the chamber of an internal combustion engine and a rod connected to said piston for movement in said longitudinal direction, a portion of said rod having a rack having a set of teeth extending transversely relative to the axis of said rod, and said movable part being an armature also having a portion in the form of a rack having teeth extending transversely relative to said axis, and said connecting means including gear means for drivingly engaging the teeth of the two said racks such that movement of the rod in one direction acts through the gear means to cause movement of the armature in the opposite direction.

3. The invention of claim 2 including a casing stationarily mounted relative to the frame of the internal combustion engine, said gear means being mounted in said casing for rotational movement about its axis.

4. The invention of claim 2 wherein said portion of said rod includes a plurality of racks equiangularly spaced about the circumference of the rod, each rack having a set of teeth extending transversely relative to the axis of the rod, and wherein said portion of said armature includes one rack for each rack of the rod means, and including a gear means for drivingly engaging each rack of the rod portion with its corresponding rack of the armature.

5. The invention of claim 4 including a casing stationarily mounted relative to the frame of the internal combustion engine and generally surrounding the rod, said armature being generally annular and surrounding the said casing, and wherein each said gear means is mounted in said casing for rotational movement about its axis.

6. The invention of claim 4 wherein said portion of the rod includes four racks.

7. The invention of claim 1 wherein said movable part comprises an armature which surrounds the said piston means and is supported with its center on said axis solely by said connecting means.

8. The invention of claim 1 wherein said piston means includes a rod mounted for movement in said longitudinal direction and having a plurality of racks spaced equiangularly about the surface of the rod, and wherein the movable part of the generator includes an armature which surrounds the rod and includes a rack corresponding to each rack on the rod, a casing stationarily mounted relative to the frame of the internal combustion engine and located between the rod and the armature, said connecting means including gear means drivingly engaging each said rack on the rod with its corresponding rack on the armature, said gear means being mounted in said casing for rotational movement about its axis.

9. The invention according to claim 8 wherein said gear means constitutes the sole means of support for supporting the armature and centering the same relative to the said axis.

10. The invention of claim 1 wherein said piston means includes at least one piston operable in the cylinder of

an internal combustion engine, said piston including a flow packing means.

11. The invention according to claim 1 wherein said piston means includes at least one two-stroke piston operable in the cylinder of an internal combustion engine, wherein during one stroke of the piston the piston acts to scavenge spent gases from the cylinder.
